UNITED STATES PATENT OFFICE.

FRANK M. HILGERINK, OF CHICAGO, ILLINOIS, ASSIGNOR TO HARRY S. HART AND CHARLES F. FITTS, BOTH OF CHICAGO, ILLINOIS.

CLEANING MEANS.

Application filed May 5, 1922. Serial No. 558,655.

To all whom it may concern:

Be it known that I, FRANK M. HILGERINK, a citizen of the United States, residing at Chicago, in the county of Cook and State of Illinois, have invented certain new and useful Improvements in Cleaning Means, of which the following is a specification.

The present invention relates to cleaning means.

More particularly the present invention relates to an apparatus for carrying out the process for cleaning surfaces as described in the Durham and McGuirk Patent No. 1,113,967, granted October 30, 1914, this process being more particularly adapted for cleaning the surfaces and moving parts of locomotives and other railway equipment and it consists in the ejection from a suitable nozzle of a stream of air, oil and water at high velocity. An essential feature of the process is that the oil, which is carried in minute quantities by the water, shall be broken up into an extremely minute condition, probably into the condition known as colloidal, so that the stream ejected from the nozzle consists of a colloidal suspension of oil in water and air at high velocity.

My present invention relates to an improvement in the nozzle of the apparatus for carrying out this process and has for its object to provide a nozzle in which the breaking up of the oil into the so-called colloidal condition shall be more effectively made by the contact of the air stream with the oil and water stream, and to produce a nozzle in which the combined stream of air, oil and water shall be ejected from the nozzle at the most effective velocity and condition.

Further objects will appear as the description proceeds.

Referring to the drawings—

Figure 1 is a view in side elevation of one embodiment of the present invention;

Figure 2 is a top plan view of the structure illustrated in Figure 1;

Figure 3 is a sectional view taken along the plane marked by the arrows 3—3 in Figure 2; and

Figure 4 is a view in end elevation of the improved structure.

The numeral 10 indicates the main body portion of my improved nozzle provided at its forward end with an ejecting portion 17,

which ejecting portion is turned downwardly at an angle to the main body portion.

The main body portion 10 is provided with a separate wall 11 which divides this portion into two passageways 12 and 13. The rear wall of passageway 12 is provided with an aperture suitably screw-threaded for the reception of a pipe 14 through which the oil and water mixture, under pressure, may be supplied to the said passageway. The passageway 13 has a similar aperture in its rear wall for the reception of a pipe 15 through which air, under pressure, may be admitted to said passageway 13. Said pipe 15 may extend through an apertured lug 16 integral with the rear portion of the nozzle whereby to provide a more or less rigid connection between the pipes 14 and 15 and the nozzle.

The passageways in the body portion terminate at their forward ends in a chamber 20, enclosed by the walls of the ejecting portion 17 of the nozzle. Said ejecting portion 17 is provided with an elongated slot 18 for the projection of the mixed stream of oil and water and air. The walls of the nozzle 20 will preferably be flared as indicated in Figure 2 to provide passageways which increase in width transversely toward the ejecting end of the nozzle. Thus the passageways within the body portion 10 are elongated transversely considering the apparatus in the position shown in Figure 3, although it will be understood that these passageways may be of uniform cross section if desired. In practice, the pressures of the air and the oil and water mixture are substantially equal. It will be noted that the separating wall 11 is elongated for a considerable distance, terminating at the rear end of chamber 20. By reason of the structure described a flat stream of air will communicate with a flat stream of oil and water mixture in the chamber 20 at a point adjacent the ejecting aperture of the nozzle and just prior to the ejection of the combined stream, so that the mixing of the air stream with the oil and water stream will occur with the formation of a minimum of eddy currents within the nozzle. I have found by experience that it is desirable to eject the colloidal suspension of the oil and water stream as quickly as possible after this colloidal suspension has been formed by

the action of the air upon the oil and water mixture. My improved nozzle accomplishes this result as the absence of eddy currents and the ejection of the stream immediately after the oil has been placed in colloidal suspension, so-called, produces a most efficient result and provides a means for carrying out the process of Durham and McGuirk patent hereinbefore mentioned to a highly efficient degree.

It will be noted further that the configuration of my nozzle is such as to provide a forward portion including the ejecting portion 17 of a comparatively uniform slight cross section, that is to say, the upper wall of the nozzle is carried backward to the point which I have marked 21 at a comparatively small angle, the angle being increased at the point 21. The advantage of this structure is that it enables the operator to insert the nozzle between the spokes of locomotive wheels and in the comparatively narrow passageways in the machinery parts, thus enabling him to direct the cleaning stream against portions of the machinery which are ordinarily more or less inaccessible.

A cleaning plug 19 may be provided in the underside of the apparatus whereby cleaning of the projecting means may be facilitated.

It will be understood, of course, that if

preferred the apparatus may be designed with a series of holes instead of the slot 18. Other modifications may be made in the illustrated embodiment of the invention without departing from the spirit of said invention. It is intended in this patent to cover all such modifications that fall within the scope of the invention as defined by the appended claim.

I claim:

Apparatus of the class described comprising a nozzle having a flaring contour from the rear portion thereof to the ejecting portion thereof, said nozzle being provided with upper and lower walls continuously progressively slanting toward one another from said rear portion of said nozzle toward the ejecting portion of said nozzle, and an intermediate flat wall dividing the interior of the nozzle into two chambers for directing flat parallel streams of fluid, said chambers being enlarged in a direction normal to said flat streams at the rearward portion of said nozzle, said flat wall extending to a position close to the region of ejection of said nozzle.

Signed at Chicago, Illinois, this 2nd day of May, 1922.

FRANK M. HILGERINK.
